UNITED STATES PATENT OFFICE.

ADOLPH L. NELSON, OF INDIANAPOLIS, INDIANA, ASSIGNOR OF ONE-THIRD TO
CHARLES S. CRAWFORD, OF INDIANAPOLIS, INDIANA.

PISTON.

Application filed March 7, 1921. Serial No. 450,189.

To all whom it may concern:

Be it known that I, ADOLPH L. NELSON, a citizen of the United States, residing at Indianapolis, in the county of Marion and 5 State of Indiana, have invented certain new and useful Improvements in Pistons, of which the following is a specification.

My said invention relates to pistons for engines, particularly for use in internal 10 combustion engines. In such engines a great deal of heat is evolved in the cylinders, causing both cylinders and pistons to expand. With cast iron pistons this is not excessive and they may fit the cylinders 15 fairly close at all times. With pistons of highly expansible metal, such as aluminum alloy, for example, much more clearance must be allowed, the expansion of the piston being materially greater than that of the 20 cylinder. Some of the larger pistons are water-cooled in present practice, but most of them are not and as the top of the piston is subjected to very high temperature in use, it is necessary that this top and adjacent parts should be materially smaller 25 than the cylinder to avoid scoring the cylinders and binding of the pistons in the cylinders. This results in excessive clearance when the engine is cool and causes a disagreeable noise in the cylinder, known as 30 "piston slap".

As the engine is heated, this noise lessens and finally disappears when the clearance of the piston in the cylinder has been sufficiently reduced.

The object of my said invention is to provide a piston construction wherein this piston slapping noise will be eliminated; also to provide a construction that will obviate the 40 leakage of oil past the cylinder head and consequent objections and also to prevent the loss of power resulting from loose pistons, all as will be hereinafter more fully described and claimed.

Referring to the accompanying drawings which are made a part hereof and on which similar reference characters indicate similar parts,

Figure 1 is a central section through a 50 piston showing one form of my improved construction,

Figure 2, a view partly in elevation and partly in section at right angles to the section of Figure 1.

Figure 3, a view similar to Figure 1, showing a modified form, and

Figure 4, a similar view showing a still further modified form.

The general form of the piston is the same in all the views only differing in details as 60 will be hereinafter more fully described.

The piston is provided with a head 5, having grooves 6 for the packing rings, and a skirt 7. It will be understood that the normal diameter of the head 5 is slightly 65 less than the largest diameter of the skirt 7, providing a clearance between the head and the cylinder to be filled or taken up by the piston packing rings as is usual. This difference in diameter is, however, difficult 70 to show on the drawings because it is so comparatively slight. As will be seen by comparing Figures 1 and 2, the skirt 7 is preferably of smaller diameter in the direction of the line of the wrist-pin than in a 75 direction at right angles with the wrist-pin, so that the wrist-pin bearings 11 may be formed in lugs which extend both outside and inside the normal line of the wall of the skirt as indicated most clearly in Figure 80 2.

Said skirt 7 is partially separated from the head by slots 8 which extend inwardly from diametrically opposite sides and parallel with the end face of the piston 85 for a distance and then curve and extend at right angles to said face to a point substantially on a line with or beyond the outer edge of the wrist-pin bearing. In the construction shown in Figures 1 and 2 it will

be noted that these slots extend only slightly beyond the wrist-pin, while in the construction shown in Figure 3 they extend for a considerable distance beyond the wrist-pin 90 and in the construction shown in Figure 4 95 a less distance beyond the wrist-pin. Their length and width may be proportioned to suit the conditions under which the piston

is to be used and the material of which the piston is made and its construction in other particulars, the purpose being in all cases to provide a skirt, the sides of which that are opposite the axial line of the wrist-pin 100 will remain practically as constant in diameter as the cylinder within which the piston is to work, or be so constructed that the contraction and expansion of the skirt due to the variation in temperature will follow

100

105

the contraction and expansion of the cylinder as closely as possible and thus maintain a uniform fit between the parts and avoid the piston slap and other troubles consequent upon a variation in clearance between these parts, such as have commonly been experienced. Said slots 8 separating the main portion of the skirt which bears against the cylinder from the piston head, 10 serve to insulate said skirt from said head and guard the skirt against the excessive contraction and expansion that would result if the skirt at these points was directly connected with said head. Said slots 8 thus 15 divide the upper portions 9 of the bearing sides of the skirt from the piston head, and as the lower or extreme outer portion of the skirt is but slightly affected by the heat from the piston head, a skirt is formed 20 adapted to be substantially constant in its diameter.

These portions 9 are braced by a bar 10 which in the form shown in Figures 1 and 2 is integral therewith and extends at right angles with the wrist-pin and above said wrist-pin connecting the upper ends of said portions 9 and holding them substantially rigid. Flanges 20 and 21 may be formed around the edges of the slots 8 to stiffen the parts and enable the skirt to be made of thinner metal than would otherwise be required. A web or brace 22 may also extend from one side of the piston head to the other, preferably joining one wrist-pin bearing 11 with the other and serve to stiffen and strengthen the head and also provide for transmission of heat through these reinforced metal parts as may be required to secure the degree of expansion necessary to maintain a uniform fit between the skirt and the cylinder.

In Figure 3, I show a construction similar to that shown in Figure 1, except that the piston head has a central depending lug 12 in which is secured the central portion of a cross brace 14, the ends of which are secured in lugs in the upper ends of the separated portions 9 of the skirt. By this means the said portions are held rigid with the center of the cylinder and the piston head is kept centrally located in respect to the side portions of the piston, and means is provided for transmitting the heat required to secure the expansion necessary to maintain a uniform fit between the cylinder and piston.

Figure 4 shows a similar construction except the depending lug 15 and cross brace 16 are integral with the head and the separated portions 9 of the skirt.

Having thus fully described my said invention, what I claim as new and desire to secure by Letters Patent is:

1. A piston for internal combustion engines comprising a head, a skirt, the skirt having slits or openings extending from immediately beneath the piston head inwardly and downwardly on each side of the wrist pin bearings to form tongues, a single brace connecting the top portions of the tongues, said tongues being unrestricted for expansion between the said upper brace and the connection of the tongue with the skirt of the piston, substantially as set forth. 60

2. A piston comprising a head and a skirt formed with openings extending transversely thereinto from opposite sides and then toward the rear of the skirt alongside the wrist-pin bearings, and a rigid brace connecting the upper ends of said separated portions, and also connected with a rigid lug centrally located on the piston head, substantially as set forth. 75

3. A piston comprising a head and a skirt with wrist-pin bearings, said skirt being also formed with slots separating the head from the bearing sides of the skirt at the upper end of said sides and an arched brace connecting said separated portions, substantially as set forth. 80

4. A piston comprising a circular head and a skirt with wrist-pin bearings and formed of smaller diameter in line with said bearings than transversely thereof and with slots separating the upper ends of the sides of the skirt opposite the axial line of the wrist-pin from the head and a brace connecting said separated portions and a web formed on the inside of the head and extending in a direction in line with the wrist-pin to join its bearings, substantially 95 as set forth. 90

In witness whereof, I have hereunto set my hand and seal at Indianapolis, Indiana this 22nd day of February, A. D. nineteen hundred and twenty-one. 100

ADOLPH L. NELSON. [L. s.]
